COMBINED FIGURINE AND ROSARY CASE

Salvatore Pisano, Massapequa, N.Y., assignor to J. S. Fitzgerald, Inc., New York, N.Y., a corporation of New York

Filed July 25, 1961, Ser. No. 66,059

Term of patent 3½ years

(Cl. D29—23)

The dominant feature of the design lies in the combination of the figurine and open book display.

I claim:

The ornamental design for a combined figurine and rosary case, substantially as shown and described.
